(57) **CLAIM**

I claim the ornamental design for an expandable body bag,
as shown and described.

DESCRIPTION

FIG. 1 is a top perspective view of the article, the article
being shown in a flattened and in a closed configuration;

FIG. 2 is a top view thereof;

FIG. 3 is a bottom view thereof;

FIG. 4 is a front elevational view thereof;

FIG. 5 is a rear elevational view thereof;

FIG. 6 is a right-side elevational view thereof;

FIG. 7 is a left-side elevational view thereof;

FIG. 8 is another top perspective view thereof, the article
being now shown in a partially-opened configuration;

FIG. 9 is another top perspective view thereof, the article
being now shown in an expanded and in a closed configura-

tion;

FIG. 10 is a top perspective view of another variant of the
article, the article being shown in a flattened and in a closed
configuration;

FIG. 11 is a top view thereof;

FIG. 12 is a bottom view thereof;

FIG. 13 is a front elevational view thereof;

FIG. 14 is a rear elevational view thereof;

FIG. 15 is a right-side elevational view thereof;

FIG. 16 is a left-side elevational view thereof;

FIG. 17 is another top perspective view thereof, the article
being now shown in a partially-opened configuration; and,
FIG. 18 is another top perspective view thereof, the article
being now shown in an expanded and in a closed configura-

tion.

The broken lines illustrating the zipper assembly and the
interior rectangle shown as a dotted line in FIGS. 1, 2, 8 and
9, illustrate portions of the expandable body bag, that form

(Continued)

no part of the claimed design. The dashed lines in the drawings show stitching that is part of the claimed design.
